UNITED STATES PATENT OFFICE.

AUGUSTUS M. HENRY, OF NEW YORK, N. Y., ASSIGNOR, BY MESNE ASSIGNMENTS, TO
MABEL CRANE BAKER, OF STAMFORD, CONNECTICUT.

BULLETIN-BOARD.

1,043,765.

Specification of Letters Patent.

Patented Nov. 5, 1912.

Application filed July 19, 1906. Serial No. 326,854.

To all whom it may concern:

Be it known that I, AUGUSTUS M. HENRY, residing at New York, in the county of New York and State of New York, have invented 5 certain new and useful Improvements in Bulletin-Boards, of which the following is a full, clear, and exact description, such as will enable others skilled in the art to which it appertains to make and use the same.

10 This invention relates broadly to bulletin boards for communicating news to the public and refers more particularly to devices for accurately reproducing the progress of a base-ball or foot-ball game or other like 15 athletic event by indicating the travel and positions of the projectile object of play used therein, as well as the progress and positions of the several players partaking in the play.

20 One of the objects contemplated by my invention is to provide a device of the above character which will graphically reproduce each feature of the game in such manner as will enable the public or those to whose view 25 the device is exposed to readily understand the same.

Another object contemplated is to provide a comparatively inexpensive device, of such simple and compact construction that its 30 setting up and taking apart may be expeditiously accomplished.

A further object is to provide, in combination with an appropriate field of the nature of that used in the particular game to 35 be reproduced, a disk or like object which may, through means substantially invisible to the public, be shifted to any part of the field in coincidence with the actual movement of the ball or other object used in said 40 game.

The invention accordingly consists in the features of construction, combination of elements and arrangement of parts which will be exemplified in the construction herein- 45 after set forth, and the scope of the application of which will be indicated in the following claims.

Other objects will be in part obvious and in part pointed out hereinafter.

50 In the accompanying drawings, where is shown somewhat diagrammatically one of the various possible embodiments of my invention, Figure 1 is a view in elevation of the rear face of the supporting wall in such

embodiment. Fig. 2 is a view in front elevation of the same, showing in dotted lines the various wires, the source of electricity, switches, etc., employed in carrying out certain of the objects of my invention. Fig. 3 is an edge view of the device, and Fig. 4 is 60 an enlarged view of one of the scoring devices.

Similar reference characters refer to similar parts throughout the several views of the drawing.

65 Referring now particularly to the embodiment of my invention herein disclosed, wherein I have shown the same as adapted to reproduce a base-ball game, there is shown a wall 1, the outer surface or face of 70 which carries the representation of a base-ball field, as shown in Fig. 2 of the drawings. On this field will be observed a plurality of apertures marked to indicate the several positions occupied by the players. 75

These apertures are provided to permit of the names of the individual players being exposed therein. In the present instance, I have provided apertures through which may be exposed the names of the pitcher, catcher, and first, second and third basemen, which 85 positions are indicated by suitable characters. Extending from the base apertures are a plurality of lines outlining the shape of the "diamond," and above the diamond are the words "Right," "Center" and "Left," indicating respectively the positions on said field coinciding with corresponding areas on the actual playing field. If desired, suitable apertures may be provided 90 for exposing to the public the names of the fielders. In the present instance, below the diamond are two parallel horizontal rows of apertures, one row being located above the other, each of said apertures, with the ex- 95

ception of the one to the extreme right from the front of each row, being adapted to have exposed therein devices to indicate the "run" score by "innings." The said right-hand apertures are adapted to have exposed 100 therein the names of the teams playing one against the other, one name in each, the scores of each team being of course exposed in the row which extends horizontally with its name aperture; said scores being indicated, preferably, by scoring members such as shown in Fig. 4, adapted to be supported 105 behind the apertures by means of pockets

disposed upon the back face of the board as shown. It will be understood that above these apertures will be placed figures or numbers to indicate their significance, and it will also be understood that at suitable places upon the board, if desired, can be formed other apertures to indicate the individual names of the players participating in the game, or a suitable aperture can be formed for exposing therein the names of the players "at bat," during the progress of the game.

It will of course be understood that while in the present embodiment of my invention I have shown apertures provided in the wall through which the names of the players may be exposed, such names may be written or printed directly upon the board and, if desired, electric lights or other indicating devices can be positioned adjacent the names of the players so that by their luminosity they may indicate the particular player "at bat" or "on base."

Wall 1 is adapted to be rigidly fixed in an upright position upon its lower end or base 2 upon a balcony or other similar place unobstructed to the view of the public. In this illustrative embodiment of my invention, I position upon the back or rear face 30 of the wall a system of pantograph levers or the like in such manner that a movement of the handle 3 upon a miniature field 4 provided upon the rear face of the wall will cause a corresponding but increased movement of the disk 5 upon the large field upon the opposite side of the wall. This disk is supported slightly raised from the surface of such large field by means of a thin, practically invisible wire 6, which is connected 40 to one end, as at 11, of the system of pantograph levers. This system of pantograph levers comprises levers 7, 8, 9 and 10. Lever 7 is pivoted to lever 8 as at 12, lever 9 to lever 7 as at 13, and levers 8 and 10 to each 45 other as at 14. Levers 9 and 10 are pivoted together as at 15, and the entire system is connected to the wall at the proper point conveniently as at 15. A suitable handle 3 on the lever 8 carries the usual pointer or 50 tracer and occupies a given position upon field 4, and disk 5, on account of the adjustment of the pantograph mechanism, will rest over a corresponding point upon the larger field upon the opposite side of the 55 wall, and a movement of handle 3 to any part of the miniature field will entail a corresponding and increased proportional movement of disk 5 to a like part of the exterior field. In the present instance, the 60 pantograph mechanism is retained in place by means of suitable guides or retaining members 16.

Pockets as at 17 are formed upon the back of the wall behind each of the several apertures formed therein, said pockets being

adapted to receive slides of the character indicated in Fig. 4. Similar pockets 17^a in the present instance are provided back of the apertures adjacent the positions occupied by the players comprising the "batteries." In this embodiment of my invention I have also provided a plurality of visual signals which in the present instance are constituted by electric light bulbs. For instance, three of these bulbs *a*, preferably of the same color, are disposed below the homeplate to indicate by their luminosity the "strikes" thrown by the pitcher; and four similar bulbs *b*, preferably of another common color, are therebelow located and adapted to indicate by their luminosity the "balls" thrown by the pitcher. Each of these bulbs is adapted to be thrown on or off at will by means of switches, A controlling the currents B from a suitable battery C in the present instance indicated in dotted lines as being upon the back of the board. Additional signals in the present instance, in the form of electric lights, are located adjacent the base positions disposed at the apices of the "diamond." These lights similarly are adapted to be thrown on or off by suitable switches provided on the back of the board and are adapted to indicate to the public the occupancy of these points by 95 base-runners.

The progress of the game may be indicated in accordance with my invention in various ways which will of course vary with the character of the game or other event which is to be reproduced. In the present embodiment it will be understood that the travel or position of the ball upon the field will be indicated by the movements of the disk 5 thereover as controlled by the movement of handle 3 under the control of the operator, who will be in communication with an observer of the actual game being played or event occurring. Other features, as "balls," "strikes," "base-hits," etc., will be indicated by the movements of the disk in conjunction with the electric light bulbs. Certain other features of the game will be indicated by the movement or position of the disk or the electric light 115 bulbs individually.

I desire it to be understood that my invention contemplates the employment of any means which will perform the functions of the projectile disk mentioned and such means is embraced within this description, such as, for instance, the equipping of the field in any of the embodiments with a series of electric light bulbs leading radially from the pitcher's box or other suitable location to various points in the field, any or all of which said series may be lighted by lighting the bulbs in each series independently in succession beginning at either end of a series. These lights may be un- 130

lighted, collectively or independently, by means of a switching means or the like within reach of the operator.

It will accordingly be seen that I have 5 provided a device of the above character well adapted to attain the several ends and objects of my invention. By means of my improved bulletin board, it will be possible for 10 an observer to follow the progress of the game or event and obtain an accurate understanding of each of the plays without the necessity of attendance at the actual scene of playing, and by reason of the simplicity of the device and the fullness with which 15 the reproduction is carried out, few if any of the features of the game are left to the imagination of the observer. Moreover, the apparatus is arranged in such manner that the same may be carried out by a single operator 20 from a position behind the wall obscured from the view of the observer. In the present instance, the operating mechanism is shown as being located behind the wall, although it is obvious that a different arrangement of this mechanism may be provided without departing from the scope of 25 my invention.

As many changes could be made in the above construction and many apparently 30 widely different embodiments of this invention could be made without departing from the scope thereof, it is intended that all matter contained in the above description or shown in the accompanying drawings 35 shall be interpreted as illustrative and not in a limiting sense. It is also to be understood that the language used in the following claims is intended to cover all of the generic and specific features of the invention herein described and all statements of 40 the scope of the invention which, as a matter of language, might be said to fall there-between.

Having described my invention, what I 45 claim as new and desire to protect by Letters Patent is:

1. A wall having on one side the representation of a base ball field and a device to represent the movement or position of the 50 ball on said field, and having a system of pantograph levers and a smaller representation of the field upon the opposite side, said levers being suitably attached to said wall and arranged to have one part of the system 55 pass over the smaller field and another part attached to said device.

2. A wall having on one side the representation of a base ball field and a device to represent the movement or position of the 60 ball on said field and on the other side thereof a smaller representation of the field, said wall being constructed to have exposed thereon informative data with reference to the progress of the game and being further 65 provided with a plurality of electric light

bulbs arranged on said wall and suitably connected with a source of electricity to indicate by their luminosity the "balls" and "strikes" thrown by the pitcher during the game, and a system of pantograph levers 70 suitably attached to said wall and arranged to have one part of the system pass over the smaller field and another part attached to said device.

3. In apparatus of the class described, in 75 combination, a wall having upon opposite sides representations of game fields, said representations being drawn upon different scales, a device located upon one of said fields adapted to represent the movement or position of a ball over said field, and means adapted to move to any part of the other field and adapted when moved to cause a corresponding movement of said device over 80 said first-mentioned field.

4. In an apparatus of the character described, in combination, a support having a plurality of ball game field representations upon the support, an indicating device located upon one of said fields and freely movable to any portion thereof and indicating by such movement certain features of the game, and a device freely movable to any portion of the other field attached to said first mentioned device, and adapted to cause 90 a corresponding movement thereof over its field, and means for supporting said devices from the first mentioned support.

5. In apparatus of the class described, in combination, a wall having a representation 100 of a game field thereon and an indicator movable to any part of said field, and co-acting with said field to indicate certain features of the game, means connected with said indicator and operated from behind the 105 wall adapted to move the same over said field, and separate signals adapted to be operated to lend significance to the movements of said device.

6. In apparatus of the class described, in 110 combination, a wall having thereon a representation of a game field and a device adapted to indicate the movements of a ball over said field and adapted to have a movement to any portion thereof, said wall having a 115 smaller but similar field located upon the opposite side thereof, and means movable over the smaller field and connected with said device adapted when moved to cause corresponding movements of said device.

7. In apparatus of the class described, in combination, a wall having upon one side thereof a representation of a game field and upon its opposite side the representation of a similar game field but upon a smaller 125 scale, a device upon the first-mentioned side of said wall adapted to represent the movement or position of a ball over its field, a system of levers supported upon the opposite side of said wall, one end of said sys- 130

tem being movable over the smaller field and the other end thereof extending beyond the edge of the wall, and a wire or other suitable member connecting said projecting end 5 of said system with said device.

8. In a device of the class described, in combination with a wall having a field which is adapted to be exposed to the view of the public of a signal adapted to be progressively movable to any part of said field and coöperating therewith to indicate certain features of the game, means operable from a position obscured from the view of the public for operating said signal, and 10 separate signals adapted to be operated to lend significance to the movements of said device.

9. In a device of the character described, the combination with a board having a field 20 representation, of an indicator adapted to be moved over the field indiscriminately to any point thereof, mechanism beyond the field for operating the indicator, and a thin member forming a substantially invisible supporting connection between the indicator 25 and said mechanism.

10. In a device of the class described, a surface having thereon the representation of a ball field, a device movable thereover 30 to indicate the movement of a ball, a second similar representation to the representation first mentioned, and means comprising a view non-obstructing part connected to said device and also having a part thereof movable over said second mentioned representation 35 and adapted to maintain between said device and said portion corresponding movements with relation to direction irrespective of the ratio of the lengths of said respective 40 movements.

11. In a device of the character described, a board having a field representation on the front thereof, an indicator adapted to move thereover, means for moving the indicator, 45 comprising a part arranged at the rear of the field, and intermediate means operated by said part and connected with the indicator whereby a movement of said part will cause a relatively greater movement of the 50 indicator.

12. In a device of the character described, the combination with a board having a field on the front thereof, of means adapted to be projected over the field to indicate the position 55 of a ball play on a field, and mechanism mounted at the rear of the field for moving the projecting means indiscriminately to any part of the field.

13. In a device of the character described, 60 the combination with a board having a field on the front thereof, of means adapted to be projected over the field to indicate the position of a ball play on a field, a device located rearwardly of the field for shifting the posi-

tion of said projecting means, and means 65 operated by said device for causing the projected means to travel a distance greater than the distance traveled by the said shifting device.

14. In a device of the class described, a 70 board having a field, an indicator adapted to play over the field, operating mechanism for the indicator which is pivotally mounted upon the rear of the board, and connecting means between the indicator and the operating mechanism which extends beyond the bounds of the field.

15. In a device of the class described, a 75 board having a field, an indicator adapted to play over the field, operating mechanism 80 for the indicator which is pivotally mounted upon the rear of the board and which extends from the indicator in a plane substantially parallel to the plane of the board, and non-view obstructing connecting means between the indicator and the operating mechanism 85 which is carried by the operating mechanism.

16. In a device of the class described, a 90 board having oppositely-facing fields, pivotally-supported mechanism comprising relatively movable parts adjacent one of said fields, an indicator positioned adjacent the other of said fields, and connecting means 95 between the indicator and one of the relatively-movable parts of said mechanism.

17. In a device of the class described, a 100 board having oppositely-facing fields, an indicator adapted to play over one of said fields, operating mechanism comprising relatively-movable parts and pivotally supported on the rear of the board, one of the relatively-movable parts being adapted to play over the other of said fields in a plane 105 substantially parallel to the plane of the board, and connecting means between the indicator and one of said relatively-movable parts.

18. In a device of the class described, a 110 board having a plurality of fields, one at the front and the other at the rear thereof, an indicator adapted to play over one of said fields, pivotally supported operating mechanism for the indicator comprising relatively 115 movable parts adjacent one of said fields, and connecting means between the indicator and the operating mechanism carried by the operating mechanism.

19. In a device of the class described, a 120 board having a plurality of fields, an indicator adapted to play over one of said fields, pivotally-supported operating mechanism for the indicator comprising relatively movable parts adjacent one of said fields, and extending in a plane substantially parallel 125 to the plane of the board, one of said relatively movable parts being adapted to play over a second field, and non-view obstruct-

ing connecting means between the indicator and the operating mechanism which extends beyond the bounds of said mentioned fields.

20. In a device of the class described, a board having a field on its front and a field representation at the rear of the first mentioned field, an indicator adapted to play over the front field, operating mechanism for the indicator pivotally mounted upon the rear of the board, and means for suspending the indicator from said operating mechanism.

21. In a device of the class described, a board having a field, an indicator adapted to play over the field, operating mechanism for the indicator pivotally mounted upon the rear of the board, a member carried by said operating mechanism which extends from the rear to the front of the board, and means for suspending the indicator from said member.

22. In a device of the class described, a board having a field, an indicator adapted to play over the field, operating mechanism for the indicator pivotally mounted upon the rear of the board, a member carried by said operating means which extends from the rear to the front of the board, and supporting means for said indicator extending from said member over the field.

23. In an apparatus of the character described, the combination of a board having upon one surface field representations, a ball indicator upon said surface, and means for moving said ball in longitudinal and transverse directions relative to the field comprising a member connected with said ball indicator and extending over the front surface of the board to a point beyond the field, and an operating means connected to said member, said means being mounted at the rear of said board.

24. In an apparatus of the character described, a movable indicator, a board over which the indicator passes, a guide, a device mounted to move on said guide, and means comprising a non-view obstructing element

whereby a movement of the device on said guide a given distance will result in a movement of the indicator a different distance. 50

25. In a device for portraying movements of a ball on a ball field, the combination with a wall having depicted thereon a ball field, indicating means positioned in front of the field, and means comprising relatively movable members extending laterally beyond the field for moving said indicating means indiscriminately to any part of the field, one of said members being substantially invisible. 55

26. In a device for illustrating the movement of a ball on a ball field, the combination with a surface having represented thereon a ball field, means for representing a ball as being played over the field, and mechanism comprising relatively movable parts arranged visibly beyond the field and associated with said ball representing means for moving the same indiscriminately to any part of the field. 60

27. A device for indicating the progress of a game of ball comprising a surface adapted to receive the representation of a ball field, a ball representation and mechanism for indiscriminately moving said representation to any part of the field to indicate different positions of the ball on the field and so without obstructing the view of the field. 70

28. In a base ball bulletin board, the combination with a board having a ball field representation thereon, of means for projecting the representation of a ball to any part of the field, said means comprising operating instrumentalities located visibly beyond the field and a non-view obstructing element between the projected ball representation and said operating instrumentalities. 80

In testimony whereof I affix my signature, in the presence of two witnesses.

AUGUSTUS M. HENRY.
